UNITED STATES PATENT OFFICE.

JOHN N. DERBY, OF BROOKLYN, ASSIGNOR TO THE HAYDEN & DERBY MANUFACTURING COMPANY, OF NEW YORK, N. Y.

STEAM-INJECTOR.

SPECIFICATION forming part of Letters Patent No. 484,303, dated October 11, 1892.

Application filed May 6, 1892. Serial No. 432,071. (Model.)

To all whom it may concern:

Be it known that I, JOHN N. DERBY, of Brooklyn, in the county of Kings and State of New York, have invented certain new and useful 5 Improvements in Steam-Injectors; and I do hereby declare the following to be a full, clear, and exact description of the invention, such as will enable others skilled in the art to which it appertains to make and use the same.

10 This invention contemplates certain new and highly-useful improvements in steam-injectors, and relates to that class known as "double-jet" machines of the nature shown and described in my pending application for 15 patent, filed March 11, 1892, Serial No. 424,691.

The present invention has for its object the production of a double-jet injector in which the overflow-valve of the lifting apparatus will be automatically closed and held to its 20 seat by the pressure in the discharge-chamber of the forcing apparatus, and the overflow-valve of the forcing apparatus is seated concurrently with the opening of the steam-inlet valve or valves of the forcing apparatus.

25 The invention consists in a double-jet injector having an automatic overflow-valve for the lifting apparatus independent of the forcing apparatus, and which will be held to its seat when the latter apparatus is working by 30 the discharge-pressure thereof, which latter is equal to the boiler-pressure.

The invention further consists in a double-jet injector having an automatic overflow-valve for the lifting apparatus and a positively-operated valve for the forcing apparatus provided with a stem connected to and moving in conjunction with the steam-inlet valve of the forcing apparatus.

35 The invention also comprises the detail construction, combination, and arrangement of parts, substantially as hereinafter fully set forth, and particularly pointed out in the 40 claims.

In the accompanying drawings, Figure 1 is 45 a vertical longitudinal sectional view of my improved injector. Figs. 2, 3, and 4 are sectional views taken, respectively, on the lines $\alpha\alpha$, $\gamma\gamma$, and zz , Fig. 1.

50 Referring to the drawings, A designates the casting or casing, which (like the steam-inlet valves and tubes employed) is substantially

the same in construction and arrangement as what is shown and described in my above-mentioned pending application for patent, and hence only brief reference thereto will be made. 55 At one end of this casing is the steam-chamber b , opening into a secondary chamber b' , which communicates through a cored passage b^2 with a lower steam-chamber b^3 of the lifting apparatus B. Of the lifting apparatus b^4 60 is the steam-inlet tube; b^5 , the valve therefor; b^6 , the combining-tube; b^7 , the delivery-tube formed with the combining-tube; b^8 , the water-chamber, and b^9 the discharge-chamber. The valve b^5 is used solely for regulating the 65 amount of steam to the lifting apparatus in order to govern the capacity of the latter.

C is the forcing apparatus, of which D is the steam-inlet tube; d , the main steam-inlet valve therefor; d' , the primary valve seated in the 70 main valve; d^2 , the valve-stem projecting through the end wall of the casing; d^3 , the combining tube; d^4 , the delivery-tube; d^5 , the water-chamber, and d^6 the discharge-chamber, in the outer end of which is a check-valve d^7 75 to prevent backflow from the boiler. The discharge-chamber b^9 of the lifting apparatus opens directly into or communicates with the water-chamber d^5 of the forcing apparatus. Extending longitudinally through casing A 80 is a core or shell E, forming a continuous chamber e , which opens at its inner end into an overflow duct or passage-way e' , leading from the delivery-chamber d^6 of the forcing apparatus to the overflow arm or branch e^2 . 85 This core or shell extends across the passage-way between the discharge-chamber b^9 of the lifting apparatus and the water-chamber d^5 of the forcing apparatus, the communication between said chambers being around said 90 core or shell.

F is the overflow-valve for the lifting apparatus. This valve is normally seated over an opening f in an upper inner wall f' of the casing and opening into a channel f^2 , leading 95 to the delivery-chamber d^6 of the forcing apparatus. This valve has a stem f^5 , which is free to move in a plug or housing f^6 , screwed in the top of casing A, and is designed to be automatically unseated by the discharge from 100 the lifting apparatus, and after the injector is started is automatically held to its seat by

the pressure in the discharge-chamber d^6 of the forcing apparatus, which pressure is equal to the boiler-pressure. In one side of the duct or passage-way e' is an opening g , coincident with the lower elongated portion g' of the delivery-chamber d^6 , and in this opening is a washer or bushing g^2 . A plug g^3 is screwed into the outer lower wall of this elongated portion, and the same is provided with

10 an inner cylindrical portion g^4 , having a series of apertures or openings g^5 therein. This plug at its inner end is designed to bear against the outer flanged portion of washer or bushing g^2 .

15 G is the overflow-valve of the forcing apparatus, the same being designed to close the overflow-opening g into the duct or passage-way, its seat being against the washer or bushing g^2 . This valve G is preferably formed integral with a long valve-stem h , which is extended through core or shell E and an opening in the end wall of the injector-casing and is connected to the yoke h' , to which is also connected the valve-stem d^2 , said yoke being 20 operated by the main operating-lever h^2 . The inner end of this valve-stem h is extended beyond the valve and is movable in an opening in a central stuffing-gland g^6 of the plug g^3 , said extended end serving as a guide for the 25 valve and its stem. The inner face of valve G is made tapered or beveled, so that it will gradually close and fit tight against its seat within the overflow-opening.

30 The operation of my present improved steam-injector as regards the steam-inlet valves is substantially similar to that of the injector embraced by my before-mentioned pending application for patent, but the difference in other respects will now be pointed out. The operator first opens the primary inlet-valve to a limited extent sufficient to permit steam to pass into the secondary steam-chamber-chamber and from thence to the lifting apparatus. The steam will pass through the latter 35 and out the discharge-chamber up into the water-chamber of the forcing apparatus, effecting the unseating of the overflow-valve, and pass into the discharge-chamber of the forcing apparatus and out through the overflow-opening thereof to the atmosphere, resulting in the creation of a vacuum in the water-chamber of the lifting apparatus and the lifting of water thereinto. The overflow-water will 40 follow the same course as the steam just outlined, and immediately upon the further opening of the steam-inlet valves, allowing steam to pass through the forcing apparatus, the column of steam and water will be gradually established and the pressure in the discharge-chamber of said forcing apparatus will hold the overflow-valve of the lifting apparatus to its seat, compelling the steam and water to pass through the combining and delivery tubes of the forcing apparatus. Simultaneously with 45 the gradual opening of the steam-inlet valves the overflow-valve G is gradually drawn to its seat, and when said steam-inlet valves

have reached the outer limit of their movement the valve G will be firmly seated, thus cutting off all overflow and causing the column of steam and water to pass on to the boiler. The main overflow-valve is additionally firmly held to its seat by the pressure in the discharge-chamber bearing against its outer flat face.

75 The advantages of my invention are apparent to those skilled in the art to which it appertains. It will be especially observed that far better and more satisfactory results are secured by the employment of an automatic overflow-valve for the lifting apparatus, and also by making the seating of the main overflow-valve positive and certain and concurrent with the opening of the steam-inlet valves, said overflow-valve moving in unison 80 with said steam-inlet valves.

77 I claim as my invention—

1. A lifting and forcing injector having an overflow for the lifting apparatus opening into the delivery-chamber of the forcing apparatus, as set forth.

2. A lifting and forcing injector having an overflow for the lifting apparatus opening into the delivery-chamber of the forcing apparatus, and a valve automatically operated 95 for opening and closing said overflow, said valve being held to its seat during the working of the injector by the pressure in said delivery-chamber, as set forth.

3. A lifting and forcing injector having an 100 overflow for the lifting apparatus opening into the delivery-chamber of the forcing apparatus, an automatically-operated valve for opening and closing said overflow, and the positively-operated valve for closing the overflow-opening of said delivery-chamber, substantially as set forth.

4. A lifting and forcing injector having an 110 overflow for the lifting apparatus opening into the delivery-chamber of the forcing apparatus, an automatically-operated valve for opening and closing said overflow, a steam-inlet valve for said forcing apparatus, having a projecting stem, and a positively-operated valve for the overflow-opening of the forcing 115 apparatus, having a projecting stem movable with the stem of said steam-inlet valve, as set forth.

5. A lifting and forcing injector having an 120 overflow for the lifting apparatus opening into the delivery-chamber of the forcing apparatus, an automatically-operated valve for opening and closing said overflow, a steam-inlet valve for said forcing apparatus, having a projecting stem, a positively-operated valve 125 for the overflow-opening of the forcing apparatus, having a projecting stem, a yoke connected to both of said valve-stems, and the operating - lever fulcrumed to said yoke, whereby said steam-inlet valve and overflow-valve of the forcing apparatus will be operated concurrently, substantially as set forth.

6. The herein-described improved steam-injector, comprising the casing, the lifting

and forcing apparatuses, the delivery-chamber of the lifting apparatus opening into the water-chamber of the forcing apparatus, the automatic overflow between said water-chamber and the delivery-chamber of the forcing apparatus, the overflow-valve of said forcing apparatus, having its stem extended on either side thereof, serving at one end as a guide, and the steam-inlet valve for said forcing apparatus, having its stem connected to and movable in unison with the stem of said overflow valve, substantially as set forth.

7. The herein-described improved lifting and forcing injector, comprising the casing having the delivery-chamber of the lifting apparatus opening into the water-chamber of the forcing apparatus, the overflow-opening over said water-chamber, the automatic valve therefor, the channel leading from said overflow-opening to the delivery-chamber of said forcing apparatus, the overflow duct or passage-way having an opening extending into said delivery-chamber of the forcing apparatus, the valve for said overflow-opening, the stem thereof extending longitudinally through the casing, and means for operating the same, substantially as set forth.

8. The herein-described improved lifting

and forcing injector, comprising the casing having the delivery-chamber of the lifting apparatus opening into the water-chamber of the forcing apparatus, the automatic overflow between said water-chamber and the delivery-chamber of said forcing apparatus, said delivery-chamber having a lower extension provided with a threaded opening, the overflow duct or passage-way having an opening into said delivery-chamber, the plug having an inner apertured cylindrical portion, the overflow-valve having a projecting portion movable in and guided by said plug, the stem of said valve, extended through a core or shell of said casing, the steam-inlet valve of said forcing apparatus, having a projecting stem, the yoke connected thereto and to the stem of said overflow-valve, and the operating-lever fulcrumed to said yoke, substantially as set forth.

In testimony whereof I have signed this specification in the presence of two subscribing witnesses.
